UNITED STATES PATENT OFFICE.

CHARLES B. JOHNSON, OF PATERSON, NEW JERSEY, ASSIGNOR TO VAN VLAANDEREN MACHINE COMPANY, OF PATERSON, NEW JERSEY, A CORPORATION OF NEW JERSEY.

MACHINE FOR TREATING FABRICS.

1,280,232.

Specification of Letters Patent. Patented Oct. 1, 1918.

Application filed August 16, 1917. Serial No. 186,534.

To all whom it may concern:

Be it known that I, CHARLES B. JOHNSON, a citizen of the United States, residing at Paterson, in the county of Passaic and State 5 of New Jersey, have invented certain new and useful Improvements in Machines for Treating Fabrics, of which the following is a specification.

This invention relates to machines for advancing a fabric or other sheet material in 10 its own plane and simultaneously singeing or otherwise operating thereon, and more particularly to machines of this general class in which the material is advanced in its own 15 plane back and forth.

One part of my invention consists in novel means for effecting the advance of the material in its own plane; another part consists in a novel means for controlling the 20 relation between the material and means to operate thereon, as brushing means, particularly with reference to reversing the direction of traverse of the material; another part consists in novel means for controlling 25 the relation between the material and means to operate thereon, as singeing means, particularly with reference to stopping and starting the advance of the material; another part consists in novel means for disposing of 30 the product, as the charred lint, of the brushing operation. The invention further consists in certain combinations and arrangements of parts whereby various operations necessary to reverse the machine are all effected from a common control means. 35

My invention is shown herein in connection with a machine for singeing and brushing fabrics wherein the fabric is advanced in its own plane from one end to the other 40 thereof first in one and then in the other direction past a singeing means and also past two brushing means arranged on relatively opposite sides of the singeing means and so controlled that in which ever direction the 45 fabric is advanced the brushing means first approached will be inactive and the other active.

In the accompanying drawings,

Figure 1 is a front elevation of the ma- 50 chine;

Fig. 2 is a rear elevation, with most of the moving parts removed;

Fig. 3 is a semi-diagrammatic front elevation;

Fig. 4 is a left-hand end elevation;

Fig. 5 is a vertical sectional view on line 5—5 of Fig. 1;

Fig. 6 is a side elevation of one of the take-up beam clutches;

Fig. 7 is a detail view of one of the brush- 60 ing appliances;

Fig. 8 is a sectional view on line 8—8 of Fig. 2; and

Figs. 9 and 10 are detail views of the feed 65 or "nip" rolls.

a is a suitable frame having at the front bearings for a horizontal drive-shaft *b* having a pulley *c* whereby it is driven and splined to it a friction wheel *d* which may be shifted thereon by a screw *e* journaled in 70 the frame and carrying a nut *f* suitably engaged with the friction wheel. At right angles to shaft *b* there is journaled in the frame *a* shaft *g* movable in its bearings toward and from shaft *b* to bring the face 75 plate *h* thereon into and out of driving contact with the friction wheel. The thrust of shaft *g* toward shaft *b* is accomplished through a lever *i* (Figs. 2, 4 and 5) from a cam *j* on a shaft *k* journaled, parallel with 80 shaft *b*, at the back of the machine. The speed of shaft *g* may be varied by adjusting the friction wheel with respect to the face plate.

Parallel with shaft *g* and at opposite 85 sides of the frame there are journaled two rolls *l* which are driven in relatively opposite directions by sprocket-and-chain connections from the shaft *g*, *i.e.*, a sprocket *m* on one roll and a sprocket *n* on said shaft 90 are connected by a chain *o*, and a sprocket *p* (Fig. 4) on the other roll and a sprocket *q* on a counter-shaft *r* are connected by a chain *s*, shaft *g* and counter-shaft *r* having intermeshing pinions *t*—*u*, respectively. 95 The fabric extends over the rolls *l*. Over each roll *l* is a pressure roll *v* journaled in a bracket *w* fulcrumed in the frame. The brackets form a part of a toggle means whereby when one roll *v* is allowed to bear 100 on the corresponding (continuously rotating) roll *l* the other will be elevated out of coacting relation to the corresponding (continuously rotating) roll *l*. The toggle means includes a rocker consisting of a transverse shaft *x* carrying a pair of V-shaped cranks *y*, and links *z* connecting corresponding arms of the cranks with the levers *w* (Fig. 3). The rocker has also a 105 crank or arm *2*, and when it is moved one 110

way or the other by means (to be described) connected with said arm 2 it will obviously cause one roll *v* to be elevated and the other depressed. In practice, the right hand advancing means serves to feed the fabric to the right, at which time the roll *v* thereof is coacting with its roll *l*, the roll *v* of the other advancing means being elevated and hence the latter is inactive; the left-hand advancing means serves to feed the fabric to the left, at which time it will be understood that the conditions just described will be reversed. The shaft *g* being driven, the fabric is advanced back and forth from one end to the other two or more times by shifting the rocker. The construction of each toggle connection is such that when one roll *v* is moved against the corresponding roll *l* the toggle connection for the other roll *v* is moved past the dead center and becomes buckled, so that the weight of the latter roll *v* holds the first in effect locked against withdrawal and pressing against its roll *l*.

In accordance with the well-known principle of machines of this type the leading end of the fabric is wound on a take-up beam, there being two such beams, one for each end of the fabric, and there are clutches whereby the beams may be disconectively connected with means for rotating them, so that one may be driven to wind up the advancing end of the fabric and the other run free to deliver the fabric. The beams are each removably supported at one end (being suitably journaled at the other end in the frame) by a head stock or mandrel 3 (Fig. 6) journaled in the frame and carrying, revolvable thereon, a driving clutch member 4 and splined thereon a driven clutch member or fork 5 adapted to be shifted by a bell-crank lever 6 into and out of clutching engagement with the member 4. Member 4, which is also a pulley, is driven continuously from a pulley 7 on the adjoining roll *l* through the medium of a belt 8. There is a stirrup rod 9 having a universal-joint connection with each bell-crank lever 6 and it carries a cushion spring 10 and above the spring a collar 11, the object of which will be explained later.

12 is a pair of parallel levers, one at each side of and suitably fulcrumed in the machine, and 13 a bar pivotally connecting them and also pivotally connected with the rocker arm 2 and having its movement with the levers in each direction limited by a spring stop 14 engaging in suitable notches in the bar (Fig. 1). The levers have outwardly projecting cranks 15 to which are pivoted collars 16 penetrated by the rods 9 and interposed between springs 10 and collars 11 thereon. When the system of parts 12, 13 is shifted to buckle one and straighten the other toggle connection, thus depressing one roll *v* and elevating the other roll

v, the rod 9 corresponding to the first toggle connection will be depressed and the other elevated to respectively engage and disengage the corresponding driven clutch members 5 with respect to the (continuously rotated) clutch members 4. The cushion spring 10 allows yielding should the fork be forced inward when opposite the lugs 4' of the driving clutch member.

There is a pair of horizontal suitably cooled guide rollers 18 arranged in the vertical central front-to-rear plane of the machine, and fulcrumed on axes in this plane is a pair of singeing devices 19, one below each roller 18; the devices 19 have reversely projecting cranks 20 which are connected by a link 21 so that the singeing devices may be conjointly shifted on their fulcras into and out of operative relation to the rollers 18 which, as will be understood, afford a suitable backing for the fabric while being singed. The shifting of the singeing devices is effected from the shaft *k* by a worm 22 thereon and an arm 23 on the lower crank 20, the arm 23 having a roller 24 engaging the worm (Fig. 8). Shaft *k* is turned in one direction to start and in the other direction to stop the machine, through the medium of parts *j*, *i*, *g*, *h* and, by the means whereby the system of parts including the singeing devices are connected with said shaft *k*, when the latter is rotated to stop the machine the singeing devices are shifted out of position for singeing (where, with the fabric stationary, it would of course be burned) and when it is rotated to start the machine they are shifted into position for singeing.

At each end of the machine there is a pair of levers 25 having their upper and lower ends connected by the pairs of links 26. A parallel lever system is thus formed. Each pair of links carries two guide rollers 27, one near each end thereof. The fabric A in the present instance extends under and over the lower and upper right-hand guide-rollers 27, respectively, then under the lower guide-roller 18, then over an idler roller 28, then under the guide-roller 18; then over an idler roller 29, and then down to the right side of the left-hand guide-rollers 27. The pairs of upper and lower rollers 27, one pair at the right and the other at the left, afford means to maintain separate taut stretches A' of the fabric, and on shifting the parallel lever system on its fulcras said stretches will shift from the planes indicated by the solid lines to those indicated by the dotted lines in Fig. 3. This has to do with the brushing means, and a further explanation thereof, in connection with said means, will follow. The shifting of the lever system is synchronized with the reversing of the direction of advance of the fabric by the following means: 30 is a lever fulcrumed in the frame

and pivoted to bar 13. It has a pin 31 adjustable in a slot longitudinally of the lever. The pin is received in the slotted end of a lever 32 fulcrumed in the frame and having 5 its other end connected with the lever system by the link 33. To vary the throw of the lever system pin 31 is adjusted in the slot of lever 30.

The brushes 34 revolve on horizontal axes 10 and are contained in housings 35 open toward the fabric. Each housing is also provided with a delivery outlet 35' at one end, to which an exhaust means may be attached. So far as I am aware this feature is new in 15 machines of this kind, in which space is wasted by exhausting means being attached radially instead of axially of the housing in the usual construction. Each brush has a pinion 36 and the several brushes are continuously rotated through a chain 37 from 20 a gear 38 (Figs. 1 and 4) fixed to rotate with the left-hand roll 7. There are four brushes, a pair (relatively to the length of the fabric) on each side of the singeing means. 25 The brushes in each pair are adapted to brush the opposite faces of the corresponding stretch A' of the fabric, and such stretch and the plane in which the axes of the brushes lie form edgewise an X. The two 30 lower brushes are between the stretches and the two upper brushes outward of them.

When the parallel lever system is shifted one way or the other from bar 13 it will be apparent that each planiform length or 35 stretch A' will move from one to the other of the solid and dotted line positions thereof shown in Fig. 3, so that according to the direction in which the shifting takes place it will be moved into contact with or away 40 from each of the corresponding brushes. By placing the pair of lower brushes between and the pair of upper brushes outward of the stretches A' the shifting of the lever system in either direction brings one 45 stretch against its brushes and the other clear of its brushes. The connections between the lever system and the bar 13 are such that according to the direction in which the fabric will be advanced the singeing 50 means that is approached by the fabric after passing the singeing means will be active and the other rendered inactive (so as not to brush and thus abrade the fabric to no purpose). Varying the throw of the lever 55 system by adjusting pin 31 in lever 30 changes the degree of pressure of the brushes on the fabric; this pressure may be altogether eliminated by adjusting the pin into coincidence with the fulcrum of lever 30.

60 The general operation of the machine will now be apparent. Having arranged two beams in the machine, one carrying the fabric to be treated, the fabric is threaded through the machine so as to stand related 65 to the feed rolls, guiding rollers and brush-

ing means, as already explained and best shown in Fig. 1, its leading end being suitably attached to the empty beam. At this time the singeing devices will occupy the position shown in dotted lines in Fig. 2, because shaft k has been turned to the position where it has caused the withdrawal of the face plate h out of contact with the friction wheel d. The operator now shifts the bar 13 to the position where the advancing 70 means, beam-clutching means and fabric stretch (A') shifting means corresponding to the empty beam will be active and the corresponding means appertaining to the full beam will be inactive. Shaft b being 75 in rotation, shaft k is turned to move the face plate against the friction wheel and throw into action the singeing devices. From now on, until the process is completed, 80 the two rolls l, driving clutch members 4 and the two sets of brushes remain continuously rotated. Each time the fabric has been unwound from one beam and wound up on the other the operator reverses the machine 85 by shifting bar 13 so that the advancing means, beam and brushes that were previously active become inactive and the other corresponding parts become active, repeating the reversing process as many times as 90 may be necessary in order to complete the singeing. 95

Suitable means is employed for supplying a combustible to the singeing means and a cooling medium to the rollers 18, but these form no part of my invention.

Having thus fully described my invention, what I claim as new and desire to secure by Letters Patent is:—

1. In a mechanism for advancing sheet material in its own plane, the combination 105 of the frame, two pairs of feed rolls, one roll in each pair being movable toward and from the other to grip and release the material, means to rotate one roll in each pair, and means to move the movable rolls simultaneously in relatively opposite directions including links respectively operatively connected to said movable rolls and a rocker arranged in the frame and operatively connected to the links, each link and rocker 110 forming a toggle.

2. In a mechanism for advancing sheet material in its own plane, the combination of the frame, two pairs of feed rolls, one roll in each pair being movable toward and from the other to grip and release the material, means to rotate in relatively opposite directions two of said rolls, one in each pair, and means to move the movable rolls simultaneously in relatively opposite directions including links respectively connected to said movable rolls and a rocker arranged in the frame and operatively connected to the links, each link and rocker forming a toggle.

3. In a mechanism for advancing sheet 130

material in its own plane, the combination of the frame, two pairs of horizontal feed rolls, one roll in each pair being movable toward and from the other to grip and release the material, means to rotate one roll in each pair, and back and forth moving mechanism coupling said movable rolls for movement together one into contact with its coating roll and the other out of contact with its coating roll, said mechanism having toggle means to lock the said mechanism on movement thereof in each direction.

4. The combination of the frame, reversible means to advance the sheet material in its own plane back and forth, separate devices to operate on the material, means to maintain separate lengths of the material planiform and shift the same back and forth simultaneously and facewise one toward one device and the other from the other device, and reversing means for the advancing means operatively connected with and adapted to shift back and forth the second named means.

5. The combination of the frame, reversible means to advance the sheet material in its own plane back and forth, separate devices to operate on the material, means to maintain separate lengths of the material planiform and swing the same back and forth simultaneously and facewise one toward one device and the other from the other device, and reversing means for the advancing means operatively connected with and adapted to swing back and forth the second-named means.

6. The combination of the frame, reversible means to advance the sheet material in its own plane back and forth, a pair of levers fulcrumed in the frame, a link connecting said levers and forming therewith a parallel lever system, means to maintain separate lengths of the material planiform including two pairs of guiding devices, one guiding device in each pair being arranged on and movable with said lever system, devices to operate on the material arranged on relatively opposite sides of said planiform lengths, and reversing means for the advancing means operatively connected with and adapted to move back and forth the lever system.

7. The combination of the frame, means to advance the material in its own plane, a pair of spaced guiding devices between

which a suitable stretch of the material is held taut, and a pair of devices for operating on the material arranged respectively opposite the faces of such stretch, one pair of said devices being shiftable back and forth relatively to the other on an axis in a plane extending between the guiding devices and parallel with said stretch, whereby to establish and disestablish contact between such stretch and the second-named pair of devices.

8. The combination of the frame, means to advance the material in its own plane, a pair of spaced devices between which a suitable stretch of the machine is held taut, a pair of devices for operating on the material arranged respectively opposite the faces of such stretch, and means to shift one pair of said devices in relatively opposite directions transversely of the plane of said stretch, whereby to establish and disestablish contact between such stretch and the second-named pair of devices.

9. The combination of the frame, means therein to advance the sheet material in its own plane, a pair of levers fulcrumed in the frame each between its ends, a pair of links connecting the corresponding ends of said levers with each other and thereby forming a parallel lever system, a set of two pairs of fabric guiding devices respectively adapted to maintain taut separate stretches of the material, and a set of two pairs of devices to operate on the material arranged one pair at one side of the plane of the axes of said levers and between said stretches and the other pair at the other side of said plane and respectively outward of said stretches, one set of said devices being arranged on the frame and the other on the parallel lever system.

10. The combination of the frame, going means to advance the sheet material therein, back and forth shiftable means to start and stop said first-named means, and a system of parts operatively connected to the second-named means for movement back and forth thereby including a pair of singeing devices fulcrumed in the frame on parallel horizontal axes and a link connecting said devices at relatively opposite sides of their fulcra with each other.

In testimony whereof I affix my signature.

CHAS. B. JOHNSON.
